HUGH B. BARBER AND WILLIAM M. HEPBURN, OF TOLEDO, OHIO, ASSIGNEES TO SURFACE COMBUSTION CORPORATION, OF TOLEDO, OHIO, A CORPORATION OF NEW YORK

COMBINED GAS BURNER AND MIXING APPARATUS

Application filed February 13, 1930. Serial No. 428,084.

This invention relates to improvements in gas burners for furnaces and has among its objects to provide a burner capable of forming and delivering, by using relatively low pressure air as the gas entraining medium, a mixture of air and gas, the relative proportions of which shall remain substantially constant over a relatively wide range of turns down; to provide a burner with which different kinds of fuel gas may be utilized with substantially equal advantage by simple adjustment of certain elements of the burner; to provide a burner wherein all of the essential elements are contained within the burner case; to provide a simple means for controlling the supply of secondary air to the mixture formed within the burner case; to provide a simple means for controlling the flow of gas to the mixing tube; and to provide a burner which shall be simple in construction and capable of manufacture at relatively low cost.

The nature of the invention will be best understood when described in connection with the accompanying drawings, in which:

Fig. 1 is a top plan of the improved burner;

Fig. 2 is an end elevation of the gas and air inlet end thereof;

Fig. 3 is an axial section of the burner on line 3—3 of Fig. 2;

Fig. 4 is a transverse section on line 4—4 of Fig. 3;

Fig. 5 is an enlarged view of a detail of the burner; and

Fig. 6 shows the improved burner applied to a furnace known in the art as a soaking pit.

The burner is generally indicated at B in Fig. 6 and is shown as positioned to discharge

through a furnace wall 10 having an aperture wherein the discharge end of the burner may be positioned for discharging the combustible mixture into a combustion tunnel 12 opening into the furnace chamber C.

In the case of a soaking pit as illustrated, it is desirable to provide an expansion flame chamber 14

in order that the highly heated gases may enter the ingot chamber with reduced velocity.

16 indicates a laterally movable roof for the pit; 18 the flue opening and W the

work or ingots to be heated. 20 indicates the

air supply pipe and 22 the gas supply pipe for the burner.

In accordance with this invention the air will be supplied to the burner under relatively low pressure by any suitable means, not shown, and the gas will be supplied at substantially atmosphere pressure by means not shown.

Turning now to the details of construction of the burner itself, it will be seen that there is provided a main casing 26 which is substantially circular in cross section, there being provided a radial flange 28 intermediate the ends thereof to permit securement of the burner to the furnace wall. The casing is an open-ended affair, one end being closed by a removable cover plate 30 to permit insertion and removal and adjustment of a Venturi entraining tube 32 which is threaded into a chambered support 34, the chamber thereof being indicated at 36 and constituting a gas chamber into which fuel gas supplied by the gas pipe 22 is delivered after passing through instrumentalities presently described. The tube 32 adjacent the nozzle end 38 of the casing 26 is circumferentially beveled as at 40 whereby the tube may serve as a valve for restricting the flow of air through the adjacent end of the casing. The tube is extended beyond its beveled portion 40 as indicated at 42 whereby to form with the discharge bore or nozzle of the casing an annular passage 44 for outflow of secondary air. For holding the tube 32 in adjusted position the flange at the opposite end of the tube may be provided with a set screw 46 adapted for abutment against the adjacent wall of the chamber 36.

The tube 32 is provided with a gas intake shown as ports 33 slightly beyond its point of minimum cross section, these ports opening to the gas chamber 36. Air is delivered to the casing 26 under pressure and this air on passing through the tube 32 will entrain gas at the intake 33 from the chamber 36 with the result that there will flow from the tube a mixture of air and gas. Ordinarily though not necessarily, the gas in the chamber 36 would be maintained at atmospheric pressure in which event the air would be supplied to

the casing at about one pound pressure, this pressure differential being sufficient for proper operation of the apparatus.

A partition 50 separates the chamber 36 from the gas pipe 22, this partition being provided with an aperture whose upper end is beveled to form a seat for a hollow and apertured valve plug 52 which at its upper end is threadedly supported as at 54 in a raised apertured portion of the casing 26, the top of said portion being preferably closed by a removable plate 56. Normally the plug 52 will be seated against the partition 50 and gas from the pipe 22 will, therefore, pass through the apertures 58 in the plug and through the nozzle 60 thereof into the chamber 36. It will be noted that the nozzle is threadedly secured in the plug. This is to permit the use of different size nozzles depending on the B. t. u. value of the gas which is available for use, the higher the B. t. u. value of the gas the smaller the orifice in the nozzle. When it is desired to change the nozzle, the plug is removed from the casing, the cover 56 being removable for this purpose.

The mode of operation of the apparatus may be described as follows: The pressure of the air delivered to the casing 26 by the air pipe 20 will always be in excess of the gas pressure in the gas pipe 22 by a suitable differential, say one pound. The air passing through the tube 32 will entrain gas through the gas intake ports 33 from chamber 36, the gas intake ports being of such size that the mixture issuing from the tube will contain an excess of gas or in other words will be deficient in air for complete combustion. The reason for forming a gas rich mixture is to enable the burner to be turned down low without causing flash-back of flame into the tube. The balance of the air required for complete combustion of the mixture leaving the tube 32 flows from within the casing 26 through the annular space 44 around the discharge end of said tube. By proper axial adjustment of the tube 32, the amount of secondary air permitted to flow past the valve seat 40 can be controlled to a nicety.

The flow of gas into the chamber 36 is ordinarily controlled by the size of the orifice in nozzle 60. When a gas of relatively high B. t. u. value is to be used, a nozzle with relatively restricted orifice will be used, as indicated in Fig. 5, and when a gas of relatively low B. t. u. value is to be used, a nozzle with a relatively large orifice will be used as indicated in Fig. 3. Gas will be delivered to the inlet side of the nozzle 60 at a constant pressure and the amount of gas which flows through the nozzle will be dependent on the differential of pressure between the inlet and outlet sides of said nozzle. It will be readily apparent that by providing the proper size of orifice in the nozzle 60, the quality of the mix-

ture discharged from the tube can be readily controlled.

If at times it should be desired to produce a mixture materially richer in gas than would be produced by the flow of gas through the orifice in the nozzle 60, it is not necessary to change the nozzle to a larger size since by backing the plug 52 off its seat, an additional flow passage will be provided as will be readily understood. It will be noted that the upper side of the plug 52 is imperforate and hence the plug may be readily adjusted with respect to the partition seat without gas escaping into the atmosphere when the cover plate 56 is removed.

From the foregoing description it will be seen that the present invention provides a relatively simple and compact piece of apparatus containing within itself means for initially forming a gas-rich mixture of air and gas; means for controlling the amount of secondary air required to support combustion in the mixture; and means for readily varying the quality of the first formed mixture. It will also be noted that relatively few machining operations are required on the casing 26 and that such as are required are relatively simple.

What is claimed is:

1. In apparatus adapted to utilize air under pressure to induce a flow of gas under lesser pressure, the combination with an entraining tube having a gas intake intermediate its ends, of a gas chamber wherein the gas intake portion of said tube is contained, a casing forming an air chamber about said tube and having a nozzle adjacent which the discharge end of the tube terminates, means for supplying gas to said gas chamber, means for supplying air to said air chamber, the space relationship between said nozzle and the adjacent end of the tube being such as to form a passage through which air from within the casing may flow for supporting combustion in the mixture issuing from said tube.

2. In apparatus as set forth in claim 1, said tube being axially adjustable with respect to said nozzle for controlling the flow of air through the nozzle.

3. In apparatus as claimed in claim 1, said tube being supported by the walls of said gas chamber.

4. In apparatus as claimed in claim 1, said gas chamber being wholly within said casing, and said tube being supported by the walls of said chamber.

5. In apparatus as claimed in claim 1, means between said gas-supplying means and the gas intake portion of said tube for controlling the flow of gas into said gas chamber.

6. In combination, an entraining tube having a gas intake intermediate its ends and a gas chamber in communication with said gas intake, means for controlling the admission of gas to said chamber comprising a

chambered body adapted to restrict the effective size of the gas inlet to said chamber, said body having a relatively restricted orifice through which gas may flow into the chamber even though said body restricts the effective size of said inlet, and a pressure chamber about said tube and gas chamber for air under pressure whereby air under pressure may flow through said tube and entrain gas from the gas chamber.

7. In combination, an entraining tube having a gas intake intermediate its ends and a gas chamber in communication with said gas intake, an apertured partition dividing the chamber into gas-receiving and gas-outlet compartments respectively, a chambered body positioned in the gas-receiving compartment and adapted to restrict the effective size of said aperture, said body having a relatively restricted orifice through which gas may flow from the gas-receiving compartment to the gas-outlet compartment of said chamber irrespective of whether or not said body restricts the effective size of the aperture in said partition.

8. In apparatus for mixing air and gas, the combination of a casing forming a pressure air chamber and having a nozzle-like outlet, a gas-supply chamber within said casing, an entraining tube having a gas intake intermediate its ends in communication with said gas chamber and having its inlet end in open communication with said pressure chamber, the discharge end of said tube projecting into said outlet and being in such space-relation therewith as to form an annular passage through which air may flow from within the casing, and means supported by said casing for controlling the admission of gas into said gas chamber.

9. In combination, an entraining tube having a gas intake intermediate its ends, a gas chamber in communication with said gas intake, a casing forming an air chamber about said tube and gas chamber for air under pressure whereby air delivered to the air chamber may flow through said tube and entrain gas from the gas chamber, and a valve structure supported by the casing for controlling the flow of gas into the gas chamber.

10. In apparatus as claimed in claim 9, said valve structure being ported to permit flow of gas at all times irrespective of whether the valve proper is closed.

11. In apparatus adapted to utilize air under pressure to induce a flow of gas under lesser pressure, the combination of an entraining tube having a gas intake intermediate its ends, an air casing wherein said tube is housed, said casing having an outlet in axial alinement with said tube, the discharge end of said tube being positioned in said outlet and forming therewith an annular passage through which air may flow from the casing, and means on the exterior of said

tube adapted to restrict the flow of air through said passage.

12. In apparatus adapted to utilize air under pressure to induce a flow of gas under lesser pressure, the combination of an entraining tube having a gas intake intermediate its ends, an air casing wherein said tube is mounted, said casing having an outlet in axial alinement with said tube and an inlet for air in non-axial alinement with the tube, and a gas chamber wherein the gas intake portion of said tube is mounted.

In testimony whereof we affix our signatures.

HUGH B. BARBER.
